To all whom it may concern:

Be it known that I, Nicholas Kove, a British subject of 252 Finchley Road, London, N. W. 3, England, have invented a new, original, and ornamental Design for a Toy Bucket, of which the following is a specification, reference being made to the accompanying drawings, forming part thereof:

Fig. 1 is a perspective view of a toy bucket, showing my new design;

Fig. 2 is a top plan view thereof, partly in cross-section, most of the handle being omitted for convenience of illustration;

Fig. 3 is a fragmentary vertical cross-sectional view thereof, taken on the line 3—3 of Fig. 2, partly in cross-section, with most of the handle omitted for convenience of illustration.

I claim:

The ornamental design for a toy bucket, as shown and described.
